UNITED STATES PATENT OFFICE.

MOSES PORTER, OF LOVINGTON, ILLINOIS.

LAND-ROLLER.

SPECIFICATION forming part of Letters Patent No. 309,798, dated December 23, 1884.

Application filed March 6, 1884. (No model.)

To all whom it may concern:

Be it known that I, MOSES PORTER, a resident of Lovington, in the county of Moultrie and State of Illinois, have invented certain new and useful Improvements in Adjustable Field-Rollers, of which the following is a specification.

My invention consists in the combination, with a pair of roller-frames adapted to pivot vertically in order to conform to the inclinations of the ground, and with the tongue ordinarily used with rollers, of a pair of bars or braces adapted to secure the rollers in a parallel position, and a set of draft bars or braces to secure the same on a line horizontally and impart the motion of the horses thereto without interfering with the pivotal motion above mentioned.

In the drawings accompanying and forming a part of this specification, Figure 1 is a plan of my device. Fig. 2 is an end view, and Fig. 3 an edge view of the ends of the rollers. Fig. 4 is a perspective view of a roller-frame.

a is the seat for the driver.

b b are the rollers.

c c are the frames in which the rollers operate.

d d are cross-bars rigidly attached to tongue

e, and provided with pivotal attachments to lugs *e' e'* of frame *c c*.

f h h show the arrangement of braces used to impart the motion of the horses to the roller-frames, *f* representing a bar rigidly attached to the tongue, and *h h* representing V-shaped draft bars or braces extending from the ends ³ of bar *f* to the frames *c c*.

g g are angle-braces to strengthen bar *f*.

The bars *d d* hold the rollers in a position parallel with each other and with the tongue.

Braces *h h* and bar *f* convey the motion of ⁴ the horses from the tongue to the roller-frames.

By having one set of braces to hold the rollers in position laterally and another set to impart motion thereto, each set may be constructed of lighter material and still, from ⁴ the advantage of location, produce a better result.

I claim--

The combination, in a field-roller, of rollers *b b*, frames *c c*, tongue *e*, bars *d d*, bar *f*, and ⁵ V-shaped braces *h h*, as and for the purpose set forth.

MOSES PORTER.

Attest:

L. P. GRAHAM,
J. D. WALKER.
